UNITED STATES PATENT OFFICE.

ALEXANDER RACK, OF PHILADELPHIA, PENNSYLVANIA.

SWING.

1,172,167.

Specification of Letters Patent. Patented Feb. 15, 1916.

Application filed April 20, 1915. Serial No. 22,657.

To all whom it may concern:

Be it known that I, ALEXANDER RACK, a subject of the Emperor of Austria-Hungary, residing at Philadelphia, in the county of Philadelphia and State of Pennsylvania, have invented new and useful Improvements in Swings, of which the following is a specification.

The invention relates to a swing, and more particularly to the class of hand impelled swings.

The primary object of the invention is the provision of a swing wherein novel means is arranged for the raising and lowering of the passenger carriers thereof so that the latter are accessible for occupancy to counter balance the load, whereby minimum power will be required by an operator for actuating the swing.

Another object of the invention is the provision of a swing of this character wherein the carriers are moved in a prescribed course, and such movement is effected by a hand power arrangement operated by the occupants of one of the carriers, the swing being of novel construction to assure easy operation thereof, and also to give pleasure to the passengers when the swing is in operation.

A further object of the invention is the provision of a swing of this character wherein the hand power operating arrangement is in convenient reach of the occupants of one of the carriers of the swing so that the same can be successfully operated when the carriers are occupied.

A still further object of the invention is the provision of a swing of this character which is simple in construction, reliable and efficient in operation, strong, durable, and inexpensive in manufacture.

In the drawings:—Figure 1 is a top plan view of a swing constructed in accordance with the invention. Fig. 2 is a vertical transverse sectional view therethrough. Fig. 3 is a front elevation. Fig. 4 is a fragmentary vertical sectional elevation. Fig. 5 is a perspective view of the hanger frame for one of the carriers. Fig. 6 is a perspective view of one of the cranks.

Similar reference characters indicate corresponding parts throughout the several views in the drawings.

Referring to the drawings in detail, 10 designates the base sills, 11 the spaced vertical uprights, 12 the upper horizontal side rails, 13 the back cross rail, and 14 the braces

which constitute the supporting frame for the swing.

Mounted on the back rail 13 at the top of the frame are spaced bearings 15 in which are pivoted swinging arms or levers 16, to pairs of which are pivoted carrier frames 17 having downwardly curved front ends 18 in which are pivoted hangers 19 supporting boat-shaped passenger carriers 20, each being provided with seats 21 to be occupied by passengers.

The front uprights 11 of the frame are extended above the latter, and journaled in suitable bearings 22, on the upper ends 70 thereof, is a rotatable shaft 23 to which is fixed a guide pulley 24, and over this pulley is trained a cable 25. One end of said cable is fixed to one of a plurality of brackets 26, which are secured to the side limbs of the 75 supporting frames 17 and carry pivot shafts 27, on one of which is journaled a guide pulley 28 over which is trained the other end of said cable 25, which is also trained over a series of guide pulleys 29 mounted at intervals 80 on the frame 17, and fixed to a windlass 30, the journal 31 of which has its suitable bearing in the said frame, and is provided with a hand crank 32 so that the cable can be wound upon and unwound from the said 85 windlass 30 for the raising and lowering of the passenger carriers 20, thus it being seen that on the lowering of the carriers they will be accessible to passengers.

Journaled in the front uprights 11 of the 90 frame near the top thereof are the stud axles 33 of substantially S-shaped cranks 34, the same being loosely connected to the shafts 27 so that on the turning of the said cranks the carrier frames will be moved in a prescribed 95 course for the impelling of the carriers 20 hung therefrom, it being understood of course that the said axle 33 in the center upright 11 is rigidly connected to both of the adjacent cranks 34 and that the said cranks 100 are disposed at an angle of one hundred and eighty degrees to each other.

Extending forwardly of the supporting frame at a point elevated above the prescribed course of movement of the frames 17 105 is a rearwardly inclined crane 35 in the free end of which is journaled a guide pulley 36 having trained therover a hand impelling cable 37, one end of which is fixed to one of the hangers 19, while the opposite end has 110 connected thereto handles 38 which extend in convenient reach of the occupants of one

of the carriers 20 so that the same can be manipulated for imparting movement to the swing.

It will be apparent that when both the carriers 20 have been occupied the impelling mechanism therefor will be counterbalanced so that minimum power will be required by the occupants of one of the carriers for actuating the handles 38 to impel the swing.

10 When both of the carriers 20 have occupants the handles 38 on the free ends of the impelling cable 37 are gripped and when the carrier at the righthand side of the swing is in lowered position a pull is exerted upon the said cable 37, which raises the said carrier and through the medium of the crank 34 the said carriers are moved in an arcuate direction and on the starting of the swing the momentum will prevent a dead center 15 so that upon alternately pulling and slackening the cable 37 the said swing will be operated.

20 The carriers are lowered relative to the ground by actuating the crank 32, which operates the raising and lowering cable 25, and as one carrier descends the other is elevated so that in this manner the said carriers are accessible to passengers.

25 When the carriers have been occupied the cable 25 is slackened so as not to interfere with the impelling of the swing. The particular contour of the cranks 34 afford resiliency to the carrier frames during impelling action thereof so as to avoid undue shocks 30 and jars incident to the working of the swing. Connected to the carrier 20 at the left hand side of the swing and also to the arm 17 supporting said carrier are brace cables 39 which prevent the swinging of the 35 said carrier.

40 From the foregoing description, taken in connection with the accompanying drawings, the construction and manner of operation of the device will be clearly understood,

and therefore a more extended explanation 45 has been omitted.

What is claimed is:

1. A swing comprising a supporting frame, levers swingingly mounted in the frame, carrier frames pivotally connected to 50 the levers, carriers depending from the free ends of the said carrier frames, cranks rotatably mounted in the frame and connected with the carrier frames, and means for impelling one of the carrier frames for the simultaneous actuation of both of said carrier frames.

2. A swing comprising a supporting frame, levers swingingly mounted in the frame, carrier frames pivotally connected to 60 the levers, carriers depending from the free ends of the said carrier frames, cranks rotatably mounted in the frame and connected with the carrier frames, means for impelling one of the carrier frames for the simultaneous actuation of both of said carrier frames, and means for raising and lowering the carrier frames to permit access to the carriers.

3. In a swing, a supporting frame, carrier frames movably mounted in the supporting frame, carriers pivotally mounted in the carrier frames, means operable from one of the carriers to impart impelling action to the carrier frame, independent means for raising and lowering the carrier frames, 75 cranks controlling the course of movement of the carrier frames, and levers pivotally connected to the supporting frame and carrier frames for permitting swinging movement of the latter relative to the movements 80 of the crank.

In testimony whereof I affix my signature in presence of two witnesses.

ALEXANDER RACK.
